Amalgamated Textiles, Ltd., New York, N. Y.,
a corporation of Delaware

Application November 29, 1937, Serial No. 177,145

2 Claims. (Cl. 281—19)

This invention relates generally to books, and particularly to books known as those of the binder type.

The primary object of the invention is to provide a book structure of such type that the filler or leaves thereof as a unit may be easily and quickly removed from the binder and replaced by another set, thus permitting repeated use of the same cover or binder with various or different unitary sets of leaves.

A further object of the invention is to provide a book structure which permits of the ready removal of some or part of the leaves without destroying the effect or appearance of the book and which further permits of the addition of leaves to the unitary set.

A further object of the invention is to provide a book cover and filler member of such character and construction that the same may be readily assembled in book form to produce a neat and attractive appearance, and yet which may be quickly and easily separated from one another for the purposes above stated without the exercise of special skill, tools or implements.

With these objects in view, together with others which will appear as the description proceeds, the invention consists in the novel construction, combination and arrangement of parts, all as will be described more fully hereinafter, illustrated in the drawing, and particularly pointed out in the claims.

In the drawing:

Figure 1 is a perspective view of a book constructed in accordance with the invention, the locking key being shown removed therefrom.

Figure 2 is an enlarged fragmentary sectional view taken through the back of the book and illustrating the assemblage of parts.

Figure 3 is a similar view taken longitudinally through the book back.

Figure 4 is a view similar to Fig. 3 and illustrating a modified form of the invention.

As has been heretofore stated, the structure of my invention is directed to a book of that nature wherein the binder or cover and the filler may be easily assembled or taken apart, the invention being directed particularly to books to contain samples of cloth, paper or other materials of the same general nature. It is my purpose to provide a binder or cover of attractive appearance for the accommodation of filler leaves or sheets of samples to be displayed, and wherein these samples may be readily removed from the filler member when desired, or replaced by other

samples, without impairing the appearance of the book and without affecting its operation. It frequently becomes necessary to remove or replace one or more sheets of a sample book, and with equipment heretofore proposed this has been difficult if not impossible of accomplishment without destroying the appearance of the sample book or without the exercise of special skill or equipment. The book of my invention entirely overcomes such objections, and the detailed construction will now be set forth, reference being had to the accompanying drawing.

The binder or cover of the book includes front and back leaves or boards 5 and 6 hingedly connected to the back member indicated at 7. The back member is preferably of channel metal of light gauge and may assume U shape in cross section as shown. This back is provided with a bottom 8 of similar metal permanently secured within the bottom in spaced relation to the latter by any approved means. In the present instance this bottom 8 has upstanding portions 9 at its longitudinal edges which may be riveted or spot welded to the sides of the back 7, and it will be understood that this bottom is coextensive with the back. The front and back boards 5, as well as the back 7, may be covered with cloth or other material to add to the attractive appearance of the completed structure, such material affording means whereby the boards 5 and 6 are hingedly connected to the sides of the bottom 7.

The bottom 8 forms an open channel lengthwise of the back of the book, and within which the removable filler unit is secured. This unit includes a clip 10 of narrow gauge metal the base portion 11 of which is of substantially equal breadth with the channel formed by the bottom 8. The clip 10 is also coextensive with or possibly a trifle shorter than the length of the book back. This clip is provided with upstanding resilient jaws 12, each of which provides a shoulder 13 near its juncture with the base of the clip. The jaws 12 rise from the sides of the clip in spaced parallel relation, and the metal of which the jaws are formed is such as to exert gripping pressure upon a filler or packet of leaves 14 of cloth, paper or other material arranged between said jaws. The leaves 14 are preferably, though not necessarily, secured as by gluing or cementing to a plate 15 of a length equal to that of the clip and of a breadth to rest upon the bottom 11 of the clip between and beneath the shoulders 13 of the jaws. This arrangement permits the

body or unit of filler leaves to be slid and maintained evenly within the clip 10.

After the leaves have been inserted between the jaws 12 of the clip, the latter may be pressed toward each other so as to frictionally grip between them the body of leaves. Any preferred tool or instrumentality may be employed for this purpose, and it will be obvious that the leaves may thus be firmly bound or secured within the clip and that the latter with the leaves form a substantially unitary structure.

The means, in one form of the invention, for detachably securing the clip and its associated body of leaves within the back includes a hook member 16 depending from the base 11 of the clip near one end thereof to engage within an opening 17 in the bottom 8, and an apertured detent or loop 18 projecting from the base 11 of the clip near its opposite end. This detent projects through an opening 19 also formed in the bottom 8 and near one end thereof. A key 20 having a spring prong or finger 21 is inserted in one end of the book back with the prong engaged in the aperture of the detent 18 whereupon the filler unit is maintained secure in the back. The key 20 is provided at one end with an integral pad 22 conforming to the size and shape of the end of the book back, and preferably this pad is covered with fabric or cloth conforming to the covering of the front and back boards. The prong 21 has a spring portion as shown to bind against the bottom 8 and to hold the prong frictionally against accidental withdrawal or displacement.

Figure 4 of the drawing shows a modified form of the invention, wherein the prong 16 is disposed of and both ends of the clip are secured in the backing by means of removable keys 20 having their spring fingers 21 engaged in openings in lugs or detents 18. In other words, the removable key arrangement at one end of the book, as shown in the preferred form, is duplicated at the opposite end of the back. This arrangement may provide a more secure seating of the removable clip, and minimizes the difficulty of making the insertion that might present itself should lug 16 become bent or distorted.

From the foregoing it is apparent that a book

constructed in accordance with this disclosure is capable of accomplishing the various desired purposes. The sample leaves 14 are cut in such size and shape as to fit evenly and smoothly within the covers. Adhesive along the inner edges 5 of these leaves secures the same to the plate 15, whereupon the latter is inserted by longitudinal movement within the clip and below the shoulders 13. This insertion will be performed, however, with the jaws 12 spread apart, whereupon the said jaws are moved inwardly into secure clamping relationship with the pad or packet of leaves 14. The unit thus formed is readily inserted within the back and is held therein by the key in the manner described. Should it be 15 desired to remove comparatively few of the leaves, it is but necessary to tear them along the edges of the jaws 12 without destroying the appearance of the book. When a number of leaves are to be removed, it may be found desirable to detach the filler unit and open one or both of the jaws whereupon the removal may be facilitated. The jaws may then be reset to firmly grip the remaining leaves between them and the unit replaced within the backing. It 20 will be understood that additional leaves may be added as desired, in the same manner.

Having thus described my invention, what I claim as new and useful is:

1. In a book, a binder, a clip including a base 30 and parallel resilient jaws projecting upwardly from the edges thereof, shoulders on adjacent faces of said jaws near the lower ends thereof, a plate engageable in said clip and snugly fitting therein below said shoulders, leaves carried by said plate and adapted to be frictionally held between said jaws and means to secure said clip in the back of said binder.

2. In a book, a binder, a back for said binder, a bottom in said back, said bottom having openings therein near its ends, a clip to seat upon said bottom, a pair of loop members projecting from said clip and adapted to extend through said openings, and spring fingers insertible in the ends of said book beneath said bottom to engage in said loops to retain the clip locked upon said bottom.

RALPH H. KNAUB.
